CLAIM

The ornamental design for a panel edging strip, as shown and described.

DESCRIPTION

FIG. 1 is a perspective view of a panel edging strip showing my new design, the panel edging strip being broken in the center to show indeterminate length; FIG. 2 is an end elevational view thereof;

FIG. 3 is a perspective view of a second embodiment of a panel edging strip showing my new design; and FIG. 4 is an end elevational view thereof.

FIG. 2

FIG. 1

FIG. 4

FIG. 3
